[57] CLAIM

The ornamental design for light switch protective shield, as shown and described.

DESCRIPTION

FIG. 1 is a front elevational view of a light switch protective shield showing my new design;

FIG. 2 is a top plan view thereof;

FIG. 3 is a bottom plan view thereof;

FIG. 4 is a side elevational view thereof, the opposite side being a mirror image; and

FIG. 5 is an isometric view thereof; the wall switch and plate are shown in broken lines for illustrative purposes only and form no part of the claimed design.

FIG. 2

FIG. 1

FIG. 4

FIG. 3

FIG. 5
